J. LIEBERMAN, A. FRIEDMAN & B. ROSE.
FASTENING DEVICE FOR GARMENTS.
APPLICATION FILED AUG. 17, 1912.

Patented Apr. 27, 1915.

1,137,499.

UNITED STATES PATENT OFFICE.

JOSEPH LIEBERMAN, ALBERT FRIEDMAN, AND BENJAMIN ROSE, OF PHILADELPHIA,
PENNSYLVANIA.

FASTENING DEVICE FOR GARMENTS.

1,137,499.

Specification of Letters Patent. Patented Apr. 27, 1915.

Application filed August 17, 1912. Serial No. 715,574.

To all whom it may concern:

Be it known that we, JOSEPH LIEBERMAN, ALBERT FRIEDMAN, and BENJAMIN ROSE, all citizens of the United States, residing in the 5 city and county of Philadelphia, State of Pennsylvania, have invented a new and useful Fastening Device for Garments, of which the following is a specification.

This invention relates to supporting devices for trousers or similar garments and relates more particularly to a form of belt construction utilized in conjunction with certain novel adjuncts of the garment, whereby the waist measurement thereof is 10 susceptible of a wide variation in size and can be adjusted to fit the particular needs or requirements of the individual.

It relates essentially to a fastening or supporting device of the type shown in our 20 prior Patent, No. 1,084,353, granted July 30th, 1912, and in its specific embodiments, comprises features of construction differing therefrom and which produce a result not heretofore attained. These embodiments 25 comprise a simple, inexpensive and effective belt or supporting device for garments, such as trousers, overalls, pajamas, ladies' skirts or like garments, whereby the waist portion may be increased or diminished in size without producing puckering or folding of the material so that the exterior appearance is that of an ordinary trouser waist band and belt.

It further consists of other novel features 35 of construction, all as will be hereinafter fully set forth.

For the purpose of illustrating our invention, we have shown in the accompanying drawing one form thereof which is at 40 present preferred by us, since the same has been found in practice to give satisfactory and reliable results, although it is to be understood that the various instrumentalities of which our invention consists can be 45 variously arranged and organized and that our invention is not limited to the precise arrangement and organization of these instrumentalities as herein shown and described.

50 Figure 1 represents a perspective of a fastening device or garment supporting means embodying our invention, the same being shown as applied to a pair of trousers.

Fig. 2 represents a side elevation of the 55 same taken from the inside and showing the

garment lining broken away for purposes of better illustration. Fig. 3 represents a transverse section of Fig. 1. Fig. 4 represents a detail partly in section showing the overlapping of portions of the garment to permit proper adjustment. Fig. 5 represents a detail in perspective of one of the bearing members and its adjuncts.

Similar numerals of reference indicate corresponding parts in the figures.

Referring to the drawings:—1 designates in the present instance a pair of trousers with which our novel belt construction is adapted to be used and the waist portion 2 of the said trousers is oppositely slit or cut 70 as shown at 3 to form front and rear sections 4 and 5. This construction permits proper expansion and contraction of the dimension of the waist portion 2, and when it is desired to reduce or contract the said 75 dimensions, it will be apparent that it can readily be done by allowing the ends of the respective sections 4 and 5 to overlap, as shown in Fig. 4.

6 designates generally a belt member 80 which in the present instance is formed in two parts 7 and 8, each of which passes around a portion of the waist 2 and is maintained in operative position by means of the usual belt straps or loops 9 which are of 85 course positioned at suitable intervals for the purpose intended. The rear section 5 of the garment, as here shown, is cut away at each side, adjacent the slit 3, to form an opening 10 within which is seated a loop 11 90 of metal or other suitable material, each of said loops carrying a bearing roll 12, about which the end 14 of the respective belt sections is adapted to pass. These bearing loops 11 are each preferably secured to the 95 rear section 5 by means of a strap 15, of fabric or other suitable material, which is permanently attached to the garment by stitching 16 or the like. It will thus be seen that when the loops 11 are fixed in position within the openings 10, a free passage is provided through which the ends 14 of the belt sections 7 and 8 may pass freely and without material friction owing to the 100 roller bearing 12. Adjacent the openings 10 we preferably employ a strip of fabric 15* which serves to stiffen and reinforce the 105 waist portion at this point.

17 designates, in the present instance, a button secured to each side of the front sec- 110

tion 4, adjacent the openings 3, and to which the ends 14 are respectively secured through the medium of a buttonhole 18, whereby the belt members may readily be detached is desired, for purposes of repair or renewal. In connection with the straps 15, it will be noted that they are, preferably, inserted between the inner lining 19 of the garment and the outer fabric lining 20 to which the material 21 is also secured thereby providing an effective fastening means necessitating but a slight change in the ordinary construction of the waist band but allowing free movement of the attached loops 11.

15 In the present instance the belt section 8 is secured at its outer end to a buckle 22, of any desired or conventional type but in this particular instance we have preferred to show this buckle member as having a pair of slots 23 and 24 therein in conjunction with which is a sliding member 25 having an opening 26 therein through which the end of the belt section 7 is adapted to pass. This construction permits a secure fastening 25 or locking of the belt members to the buckle member as is apparent.

In view of the fact that the slits 3 are preferably disposed adjacent to the side pockets of the garments, it will be seen that 30 when the parts are in assembled position, as shown in Fig. 1, there will be no noticeable change apparent in the waist band as compared with the ordinary garments but the advantage of our novel construction will 35 readily be appreciated since the two sections of the belt 6 may be driven together thereby overlapping the front and rear sections 4 and 5 and causing the garments to fit snug around the waist of the wearer. A 40 further advantage is apparent in that the forward section of the garments is drawn rearwardly while the rear section is drawn forwardly and therefore when the two sections overlap there is no folding over or 45 puckering of the material around the waist and the garment appears to fit smooth and tight as should be the case.

It will now be apparent that we have devised a novel and useful fastening device

for garments which embodies the features of 50 advantage enumerated as desirable in the statement of the invention and the above description, and while we have, in the present instance, shown and described a preferred embodiment thereof which has been found 55 in practice to give satisfactory and reliable results, it is to be understood that the same is susceptible of modification in various particulars without departing from the spirit or scope of the invention or sacrificing any 60 of its advantages.

Having thus described our invention what we claim as new and desire to secure by Letters Patent, is:—

The combination with a garment having 65 side slits adjacent the hip portions to form front and rear waist sections, said rear section having on each side thereof an opening, passing entirely therethrough, at a suitable point removed from each edge of the side 70 slits, an attaching means carried on the inner face, at each side, of said front section, a loop for each opening suitably secured to said rear section, and a pair of belt members, one end of one member passing through 75 one of said openings and its loop, and extending forwardly, and being removably secured to the attaching means on one side of the front section, and one end of the other belt member passing through the other opening of the rear sections and its loop, and extending forwardly and removably secured to the attaching means on the other side of the front section, the opposite ends of said belt members extending forwardly to the 80 front of said front section, whereby the belt members are situated exterior of the edges of the slits of both the front and rear sections, and the said belt members serving to hold the edges in close contact and in a flat 85 condition, and means for securing the front 90 ends of said belt members together.

JOSEPH LIEBERMAN.
ALBERT FRIEDMAN.
BENJAMIN ROSE.
